INVENTOR:
JAMES R. POWELL,

BY ATTY:

Frederic M. Keeney.

UNITED STATES PATENT OFFICE.

JAMES R. POWELL, OF LOS ANGELES, CALIFORNIA.

BROOM SHIELD.

Application filed April 28, 1923. Serial No. 635,305.

To all whom it may concern:

Be it known that I, JAMES R. POWELL, a citizen of the United States, residing in the city and county of Los Angeles and State 5 of California, have invented a new and useful Improvement in Broom Shields, of which the following is a specification.

This invention relates to an improved broom shield, having for its objects to provide means for resisting wear and for reinforcing the broom filaments, so that the broom will retain its original shape for a long time, thereby increasing the term of usefulness of the broom.

15 Other objects are to reinforce the weak part of the ordinary broom; and thereby increase the durability and wearing qualities; to construct a shield for the broom of such flexible material as to readily allow 20 sufficient spring to the filaments to give the best results; to provide a shield adapted for advertising purposes; and to provide a shield which will neatly fit the shape of the broom to which it may be attached.

25 Another object is to provide a shield which will always hold its shape, and which eliminates fifty per cent of the dust in use.

Another object is to provide a shield which may be purchased separately and applied by the user to any broom, or which may be incorporated with the filaments in the manufacture of the broom; the construction hereinafter described in detail, allowing a maximum of flexibility to the broom 35 filaments until they are worn off to the edge of the shield.

Another object is to provide a shield of the character described, which will not injure the furniture, or other articles among 40 which the broom may be used.

To these ends, the invention consists in certain novel features of construction, combination and arrangement of parts, hereinafter more fully described and claimed.

45 In the drawings, Figure 1 is a side view of a broom to which my improved shield has been applied. Fig. 2 is an enlarged and fragmentary view of a broom to which my improved shield is applied. Fig. 3 is a 50 longitudinal and sectional view of the shield. Fig. 4 is a perspective detail view of a reinforcing element adapted to be secured

within the fabric covering forming the body of the shield. Fig. 5 is a modified form of the reinforcing element, showing 55 spikes adapted to project inwardly among the broom filaments.

In the embodiment of the invention shown, the broom handle 11, has the broom filaments 12, secured thereto by the binding 60 elements 13, in the usual manner. The shield consists of a body 14, preferably constructed from a heavy cloth fabric, and provided with eyelets 15, through which the binding elements 16, may be passed. The 65 body of the shield is provided at its lower edge 17, with an elastic band 18, extending beneath the fabric. I further provide resilient reinforcing elements 19, extending along the vertical edges of the shield. The 70 resilient elements are secured by cords 20, passing through the cloth fabric and through holes 21, in the resilient elements. These resilient reinforcing elements are preferably made of thin strips of rattan or 75 of bamboo, but any other light and inexpensive resilient material may be substituted therefor.

The shield may be attached as shown in Fig. 1, by stitching the fabric directly to 80 the broom filaments, or as shown in Fig. 2, by passing a cord 16, through the eyelets on opposite sides of the shield, and tying the cord outside of the edge of the shield, the cord 16 extending through the broom 85 filaments 12, above and below the binding elements 13. This serves to maintain the shield in position. In Fig. 2, a portion of the cloth fabric body 14, is broken away to show the binding elements 13. 90

In the modified form shown in Fig. 5, the shield is secured in position by driving in the spikes 23, into the broom filaments.

From the foregoing description and drawings, it may be seen that I have provided a simple and efficient broom shield serving as a protector both for the broom filaments and for articles of furniture among which the broom may be used. The binding cords 16, extending above and below the broom binding elements 13, may be removed when the broom filaments are worn out, and the shield may then be applied to a new broom. The resilient reinforcing 95 100

elements combined with the flexible cloth fabric, and with the elastic reinforcing element at the bottom edge of the body, serve to protect the broom until the broom filaments are worn out.

Having described my broom shield, I claim as my invention:

1. In a broom shield, the combination with broom filaments and binding elements for the filaments, of a fabric shield member enclosing the filaments, and extending above and below the broom binding elements, eyelets in the fabric and above and below the broom binding elements, binding cords passing through the eyelets and through the broom filaments above and below the broom binding elements, an elastic band forming the bottom of the shield body, and reinforcing elements within the body and extending vertically along the edges thereof.

2. In a broom shield, the combination with a fabric body, of eyelets therein and on opposite sides, an elastic band forming the bottom edge of the fabric body, resilient reinforcing strips extending within the body and vertically along the edges thereof, binding elements securing the resilient strips to the body, and binding cords

passing through said eyelets and adapted to be tied on the outer edges of the body.

3. The combination with a broom having brush filaments and binding elements for the brush filaments, of a shield body encasing the brush filaments and extending above and below the broom binding elements, eyelets in the shield body, resilient reinforcing elements extending vertically within the body and secured thereto, and binding cords passing through the eyelets, the binding cords being tied outside of the edges of the body.

4. In a broom shield, the combination with a fabric body adapted to encase the broom filaments and to extend above and below the broom binding elements, of eyelets in the opposite sides of the fabric body, vertically disposed resilient reinforcing elements within the body, horizontally disposed reinforcing means forming the bottom portion of the body, and binding cords passing through the eyelets and through the broom filaments above and below the broom binding elements.

In testimony whereof, I hereunto affix my signature.

JAMES R. POWELL.
